ARTICULATION FOR A CLOSURE DEVICE
FOR RECEPTACLES OF PLIABLE MATERIAL

Harold H. Hallock, Cayuga County, N. Y., assignor to Fa-Cile Fastener Corporation, New York, N. Y.

Application April 12, 1939, Serial No. 267,424

2 Claims. (Cl. 16—142)

My invention relates to closures for receptacles of pliable materials, such as bags, purses, etc., which will yieldingly lock self in a closed and open position.

- 5 The object of the invention is to provide a simple and inexpensive joint which may be used in conjunction with frames of resilient or rigid type, suitable for receptacles of the type referred to.
- 10 Another object of the invention is to provide a receptacle closure, the locking of the open and closed position of which does not have to depend on the resiliency of the frame members alone.

In the appended drawing, forming part of this application,

Figure 1 is a fragmentary edge view of the left end of a frame embodying my invention.

Figure 2 is a fragmentary section of the right end of the frame on line 2—2, Figure 5.

20 Figure 3 is a top edge view of the right end of the frame, showing it in open position, and

Figures 4 and 5 are fragmentary side elevations of the left and right side of the frame respectively.

Referring to the drawing, 15, 15 are the side members of the frame which in normal or closed position, are juxtaposed. These members are to be covered by a flexible material not shown, of which the receptacle is to be made.

The proximate ends of the frame members are 30 provided with a joint having an angular movement which is adapted to yield laterally, that is, in the direction of the angular movement. The joint consists of a male plate 16 and a female plate 17, each secured to a respective proximate 35 end of the frame members 15. The plate 16 has a hook 18 formed of a riser disposed angularly to the plate and an extension from the riser running toward the end of the plate. The hook is preferably flexible laterally, but not necessarily.

40 The hook 18 passes through an aperture 19 formed in the plate 17.

To each side of the hook 18, plate 16 has yielding fingers 20 deflected towards the plate 17. The ends 21 of the fingers 20 are bent at an 45 angle, so that the extremities thereof are substantially in alignment with the end of the hook 18. The plate 17 beyond the member 15 to which it is secured, is deflected toward the other plate to bear with its transverse edge 22, against the fingers 20 at the bent ends 21, in a closed 50 position of the frame. The bent ends 21 of the fingers 20 prevent the unhooking of the plate 17 from the plate 16. If desired, the plates may be entirely of resilient material.

55 In mounting the joints on the frame members,

the opposite ends of same frame members are preferably provided with different type of plates, that is to say, if one end of the frame member is provided with a male plate 16, then the opposite end of the same frame member is provided with 5 a female plate 17. This is to facilitate the assembling of the frame.

With a resilient type of frame members 15, in opening the frame a pull is exerted laterally on the members 15, causing plates 17 to turn on the 10 hooks 18 of plates 16 as a fulcrum.

As the plates 16 and 17 of the same joint are moved angularly, in opening the frame, the transverse edge 22 of the female plate 17 in each joint, while travelling from the bent ends 21 of the 15 fingers 20 toward the hook 18 deflects laterally the fingers 20 and the hook 18 of same plate 16 in opposite directions. This lateral deflection of the fingers and the hook by the turning movement of the portion of the plates 17 engaged 20 between the hook and the fingers increases the pressure by the hook and the fingers on that portion. When said portion of the plate 17 passes the dead center between the hook and the fingers it will snap under that increased pressure exerted 25 by the hook and the fingers forcing the plate 17 to snap against the base of the hook 18 into the position shown in Figure 3, that is the open position of the frame. In this position, the plate 17 is yieldingly locked by the fingers 20 and the 30 hook 18, as they normally exert pressure on the portion of the plate 17 engaged therebetween.

In moving the frame members 15 from open to closed position, the action is in reverse order to that described, that is to say, in passing the dead center between the hook 18 and the fingers 20, the plate 17 will snap to bring the frame members 15 in juxtaposed position, as shown in Figures 1 and 2, and bringing the transverse edge 22 of plate 17 in proximity of the bent ends 21 of fingers 20, 40 where it will be held yieldingly locked, due to the pressure exerted on the portion of the plate 17 engaged between the hook 18 and the fingers 20.

In other words, in both positions, open or closed, the joint is yieldingly locked and requires 45 an effort independent of the frame members for the open or closed position of the frame. It is evident that the opening of the frame shortens the distance between the joints, and in consequence the members 15, if of resilient material, 50 will be bowed and form the opening defined by the members 15. In closing the opening formed by the frame members, pressure is applied to the said members 15 preferably in proximity of the joints thereof.

From the above description it will be seen that the type of articulation described form a pintleless hinge in which there are two juxtaposed parts normally tending to yieldingly resist angular movement between said parts and adapted to lock said parts in predetermined angular positions.

I claim:

1. An articulation for a closure device comprising two juxtaposed frame members connected at the proximate ends by a pintleless joint, each joint comprising a male portion having yielding fingers and a hook positioned between the fingers and deflected from the plane of the fingers, the fingers being adapted to flex laterally, said hook being formed by a riser disposed angularly to the male portion and an extension from the riser running toward the end of the fingers, each of said fingers having a bent portion at the end thereof directed toward the extension so that the edges of the bent portion of the fingers are substantially in alignment with the end of the extension in open or closed position of the articulation and a female portion having an aperture through which the hook passes and whereby the male and female portions are prevented from separating, said female part bearing with its free end on the fingers of the male part in all angular positions of the joint when the female portion is

moved from the bent portions of the fingers to the base of the hook and vice versa as the articulation is opened or closed respectively.

2. A pintleless articulation for a closure device comprising two juxtaposed frame members providing a part at a proximate end of a frame member and formed thereat with yielding fingers, and a hook between the fingers formed of a riser disposed angularly to the part and an extension from the riser disposed angularly to the riser and running toward the end of the fingers, said hook and fingers extending beyond the frame member, said fingers being adapted to flex laterally, each of the fingers having the ends thereof bent toward the extension so that the ends of the bent portion of the fingers substantially align with the end of the extension in open or closed position of the articulation, said extension and fingers forming a substantially enclosed space between said fingers and tongue on said part, a second part at the proximate end of the other frame member and having an aperture through which the extension projects so that a section of said second part is engaged between the hook and the fingers at all positions of the articulation, said hook and fingers being adapted to yieldingly lock the second part when its end is either at the base of the extension or at the bent portion of the fingers.

HAROLD H. HALLOCK.
